PRESSING MACHINE PAD

Robert Kowser, Seattle, Wash.

Application October 26, 1939, Serial No. 301,493

6 Claims. (Cl. 38—66)

My invention relates to improvements in pads for steam pressing machines such as are used by tailors and in industrial plants for pressing and steaming clothes and fabric materials, and an important object of the present invention is to provide a more efficient and serviceable pad of this character having advantages over conventional pads of this character now in use and to be pointed out herein.

Other important objects of the invention will appear in the following description and the drawing wherein for illustrative purposes a preferred embodiment of the invention is shown.

In the drawing:

Figure 1 is a top plan view.

Figure 2 is an enlarged transverse vertical sectional view taken through Figure 1 approximately on the line 2—2.

Figure 3 is a fragmentary still further enlarged transverse vertical sectional view taken through Figure 1 and showing the component elements separated from each other to illustrate the make-up of the pad.

Referring in detail to the drawing, the numeral 5 generally designates the pressing machine pad which may have any suitable shape in plan such as the tapered form with rounded ends shown in Figure 1 of the drawing. As indicated in Figure 2 the side edges 6 and 7 are substantially straight and disposed at right angles to the top and bottom of the pad, although in practice and because of the nature of the component materials, the corners of the side edges 6 and 7 will be somewhat rounded.

The pad 5 is made up of an outer contour defining envelope 6 of muslin which encloses several superposed sections respectively designated from top to bottom by the numerals 7, 8, 9 and 10.

The section 7 is composed of about six layers 11 of loose cotton batting enclosed in a muslin envelope 12 with partitions 13 of cheesecloth separating adjacent layers. The edges of the cheesecloth partitions are unconnected with the muslin envelope 12.

Below the described section 7 is the section 8 which comprises a screen or sheet of hair cloth composed of cotton with air woven in it, the sheet being soaked in strong alum water to give it the desired toughness and rigidity.

Beneath the section 8 is the section 9 which comprises the muslin envelope 14 enclosing two layers 15 of cotton batting which are separated by a cheesecloth partition 16 which has its edges unconnected to the muslin envelope 14.

Under the section 9 is the bottom section 10 which comprises the muslin envelope 17 enclosing a top layer 18 of ordinary cotton batting and two lower layers 19 of fine cotton batting, with respective cheesecloth partitions 20 separating the layers 18, 19 and 19.

When the steam of the pressing machine is turned on into the pad the steam is caused to diffuse throughout the various layers thereby causing the pad to present a cushion with a uniform pressing surface and evenly distributed heat-pressure. Being more impervious to the steam than the other layers, the hair-cloth section or sheet 8 causes a uniform steam pressure throughout the pad, thereby also producing the cushioning action of the pad, enabling quicker and more uniform pressing of clothes and preventing the crushing and breaking of buttons and production of streaks and shine on the pressed garments.

Although I have shown and described a preferred embodiment of my invention, it is to be definitely understood that I do not desire to limit the application of the invention thereto, except as may be required by the scope of the subjoined claims.

Having described the invention, what is claimed as new is:

1. A pressing machine pad consisting of a steam permeable cushion composed of a top section comprising layers of fibrous material, an intermediate section comprising layers of fibrous material, a bottom section comprising layers of fibrous material, and a fabric screen disposed between the top and intermediate sections, the layers of the top section being composed of cotton batting.

2. A pressing machine pad consisting of a steam permeable cushion composed of a top section comprising layers of fibrous material, an intermediate section comprising layer of fibrous material, a bottom section comprising layers of fibrous material, and a fabric screen disposed between the top and intermediate sections, the layers of said intermediate section being composed of cotton batting.

3. A pressing machine pad consisting of a steam permeable cushion composed of a top section comprising layers of fibrous material, an intermediate section comprising layers of fibrous material, a bottom section comprising layers of fibrous material, and a fabric screen disposed between the top and intermediate sections, the layers of said bottom section being composed of cotton batting.

4. A pressing machine pad consisting of a steam permeable cushion composed of a top section comprising layers of fibrous material, an intermediate section comprising layers of fibrous material, a bottom section comprising layers of fibrous material, and a fabric screen disposed between the top and intermediate sections, and a overall cover of fabric material enclosing said top, intermediate and bottom sections, the various contiguous layers being separated by foraminous fabric partitions. 10

5. A pressing machine pad consisting of a steam permeable cushion composed of a top section comprising layers of fibrous material, an intermediate section comprising layers of fibrous material, a bottom section comprising layers of fibrous material, and a fabric screen disposed between the top and intermediate sections, said top, intermediate and bottom sections each being enclosed in respective fabric material envelope, 20

said sections being in superposed positions, and a contour imparting fabric envelope encasing the sections to form the pad.

6. A pressing machine pad comprising a
5 steam permeable cushion consisting of an upper
section, an intermediate section, and a lower section,
a relatively close mesh fabric envelope such as
muslin enclosing and assembling said sections,
each of said sections being enclosed by a
10 relatively close mesh fabric envelope such as
muslin, each of said sections being characterized
by a plurality of superimposed layers of com-
pressible relatively thick fibrous material such as
cotton batting with adjacent layers being sep-
15 arated by open mesh fabric partitions such as
cheese cloth, said upper section containing a
greater number of said layers than either said
intermediate section or said lower section.

ROBERT KOWSER.
